(57) **CLAIM**

The ornamental design of a chafer griddle, as shown and described.

DESCRIPTION

The present application is related to commonly-assigned U.S. Design patent application No. 29/378,379, entitled "Chafing Dish," U.S. Design patent application No. 29/378,381, entitled "Chafing Dish Frame," U.S. Design patent application No. 29/378,385, entitled "Chafer Wok," and U.S. Design patent application No. 29/378,387, entitled "Soup Chafer," which are filed concurrently herewith and which are incorporated by reference herein in their entireties for all purposes. FIG. 1 shows a perspective view of a chafer griddle showing a first embodiment of our design;

FIG. 2 shows a front elevation view of the chafer griddle of FIG. 1;

FIG. 3 shows a right side elevation view of the chafer griddle of FIG. 1;

FIG. 4 shows a rear elevation view of the chafer griddle of FIG. 1;

FIG. 5 shows a left side elevation view of the chafer griddle of FIG. 1;

FIG. 6 shows a top plan view of the chafer griddle of FIG. 1; FIG. 7 shows a bottom plan view of the chafer griddle of FIG. 1;

FIG. 8 shows a perspective view of a chafer griddle showing a second embodiment of our design;

FIG. 9 shows a front elevation view of the chafer griddle of FIG. 8;

FIG. 10 shows a right side elevation view of the chafer griddle of FIG. 8;

FIG. 11 shows a rear elevation of the chafer griddle of FIG. 8; FIG. 12 shows a left side elevation view of the chafer griddle of FIG. 8;

FIG. 13 shows a top plan view of the chafer griddle of FIG. 8; and,

FIG. 14 shows a bottom plan view of the chafer griddle of FIG. 8.
